METALLIC SPOOL

George F. Walter, Brooklyn, N. Y., assignor to
American Can Company, New York, N. Y., a
corporation of New Jersey

Application August 19, 1933, Serial No. 685,913

6 Claims. (Cl. 242—123)

The present invention relates to metallic spools for adhesive tape, medicinal bandages and the like, and has for its object the improvement and simplification of their construction, such metallic spools comprising generally a main body or core part and a pair of end pieces or heads secured to the ends of the core.

The present invention contemplates utilizing struck out spacing members or ridges in the core of the spool as backing up or folding elements for the spool heads and the side seam of the core part may also be utilized in this capacity.

The principal object of the present invention is the provision of a spool core and spool heads of simplified construction, the core wall having projecting spacing members or ridges and the ends of these ridges providing abutments for the spool heads thus making a rigid and simple holding construction for the spool parts.

The present invention has for a further object the provision of a spool assembly which may be loaded with a wound reel of tape or other suitable material prior to the final attachment of one of the spool heads, this final attachment of head then being performed with a simple spinning or bending operation.

The projecting ridges of the spool besides providing for the rigid holding construction of parts strengthen the core and also present anti-frictional supports for the reel of tape, thus facilitating its unwinding for use.

Numerous other objects and advantages of the invention will be apparent as it is better understood from the following description, which, taken in connection with the accompanying drawing, discloses a preferred embodiment thereof.

Figure 1 is an exploded, perspective view of an incomplete spool embodying the present invention and also showing a reel of material in position for assembly;

Fig. 2 is a longitudinal sectional view taken through the loaded spool, showing one of the spool heads firmly fixed to the spool core and the other head in position for final attachment;

Fig. 3 is a view similar to Fig. 2 partly broken away and illustrating the core and head after final attachment;

Fig. 4 is a transverse sectional view of the core taken substantially along the line 4—4 in Fig. 3;

Fig. 5 is an enlarged, fragmentary, sectional view taken through one end of the core and illustrating the loaded reel on the core and the head in position preparatory to final attachment; and

Fig. 6 is a view similar to Fig. 5 illustrating the head interlocked in its final engagement with the core.

As illustrated in the drawing the embodiment of the present invention comprises a tubular or cylindrical core 11 which may be formed from a metal blank having its ends secured together in a side seam 12. This side seam comprises a central spacing section or lock seam portion 13 which is pressed outwardly beyond the surface of the core as best shown in Figs. 1 and 4. The ends of the side seam comprise flush portions 14 and the ends of the lock seam part 13 constitute abutting edges 15 which are a short distance from the ends of the core.

The core 11 may also be provided with one or more longitudinal ridges 16 struck outwardly from its cylindrical wall. These ridges are the same length and extend substantially in the same manner as the lock seam part 13 of the side seam. The ends of the ridges constitute abutting edges 17 which are in the same transverse plane as the abutting edges 15 of the side seam.

Spool end members or heads 21 are provided and preferably comprise circular discs having curled outwardly disposed rims 22 and are also formed with central apertures 23. The metal adjacent each aperture 23 is turned outward into an axially extending flange 24 which is merged into an annular outwardly pressed portion 25 in the head wall as best illustrated in Figs. 5 and 6.

In forming the spool one of the heads 21 is first positioned on one end of the core 11, the core end extending into the aperture 23. The head is pushed back on the core until the wall of the annular part 25 is brought into engagement with the abutting ends 15, 17 of the side seam and spacing ridges. The outer end of the core is then curled over or bent back over the projecting flange 24 of the head as at 26 in Fig. 2.

This interengagement of the end of the core with the flange of the head provides an interlocked joint or seam 27 for the one head of the spool. This much of the assembled spool is illustrated on the left of Fig. 1. The tape or other material for which the spool is designed has previously been wound in reel form 31 (Figs. 1 and 2) in the usual manner as over a fibre tube 32.

The tube 32 is of inner diameter slightly greater than the outside diameter of an imaginary circle passing through the outer surface of the projecting parts of the side seam 12 and of the

ridges 16. The reel 31 is pushed over the free end of the core and the inner tube 32 encircles the projecting side seam and the ridges.

The opposite head 21 is then slipped over the free end of the core 11 (Figs. 2 and 5) with its flange 24 extending outwardly over the end of the core. In this position the head wall at the base of the annular part 25 is in engagement with the abutting edges 15, 17 of the parts 12, 16. The outer end of the core need then be only curled over or spun back as at 33 (Figs. 3 and 6) to provide an interlocked seam joint 34 which holds the head wall solidly against the abutting spool ridge edges.

This construction of core and head thus provides for a rigid yet simple form of support for the heads which rest at all times against the edges of the side seam and the spacing ridges. The interlocked seams 27, 34 of the spool are simple to make being a mere spinning of the core ends. The spacing ridges and these spun core ends prevent any sliding movement of the heads relative to the core.

The reel 31 is free to turn on the core 11, the outer engaged surfaces of the parts 12, 16 against the inner wall of the tube 32 being of sufficient extent to hold the reel in rotating position within the spool but not large enough to present frictional resistance against the free turning of the tube on the core. The tape and tube are of slightly less width than the distance between the spool heads held by the spacing members for this purpose.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A metallic spool, comprising a core having longitudinal struck out spacing ridges extending for substantially the length of the core and terminating short of an end of the core, and a spool head positioned on the end of said core and abutting the edges of said ridges, the end of said core being interlocked with said head to hold it firmly against the said ridge edges.

2. A metallic spool, comprising a core having longitudinal struck out spacing ridges having outer bearing surfaces parallel with the axis of the spool and adapted to form bearings for a reel, and terminating short of the ends of the core, and spool heads positioned on the ends of said core and abutting the edges of said core ridges, the adjacent ends of said core being interlocked

with the said heads and holding them firmly against the edges of said core ridges.

3. A metallic spool, comprising a cylindrical core having a side seam formed with a central locked portion and two end flush portions, the former extending out beyond the cylindrical wall of said core and terminating in abutting shoulders located adjacent to but short of the core ends, and spool heads positioned on the ends of said core and resting against the said abutting shoulders, the ends of said core being interlocked with said heads to hold the parts in fixed relation.

4. A metallic spool, comprising a cylindrical core having a side seam formed with a central locked portion and two end flush portions, the former extending out beyond the cylindrical wall of said core and terminating in abutting shoulders located adjacent to but short of the core ends, said core also having longitudinal struck out spacing ridges also extending out beyond the cylindrical wall of said core and terminating in abutting edges, and spool heads located on the ends of said core and resting against the abutting shoulders of said side seam and against the abutting edges of said longitudinal ridges, the ends of said core being interlocked with said heads to hold the parts in fixed relation.

5. A metallic spool, comprising a core having longitudinal struck out spacing ridges extending from one spool head to the other so as to form supports for a reel tube and terminating short of the ends of the core, and spool heads having central apertures surrounded by right angled flanges positioned on the ends of said core with the said flanges resting on the core and the heads abutting the end edges of the ridges, the ends of said core extending beyond said heads and being curled back and over the said flanges for holding the core and heads in fixed and assembled relation.

6. A metallic spool, comprising a core having longitudinal struck out spacing ridges terminating short of its ends, and also having a side seam formed with a central locked portion and two end flush portions, the locked portion also terminating short of the ends of the core, and spool heads having inner flanges and adjacent annular outwardly pressed parts and located on the ends of said core with said flanges in engagement therewith, the abutting end edges of said ridges and said lock seam portion resting in said outwardly pressed parts, the ends of said core being bent back over the said flanges to hold the heads in rigid position against the abutting edges of the said ridges and the lock portion of the said side seam.

GEORGE F. WALTER.
